UNITED STATES PATENT OFFICE.

HERBERT G. IRWIN, OF SPUR, TEXAS.

VACUUM-OPERATED MAKE-AND-BREAK SPARK-PLUG.

1,285,199.

Specification of Letters Patent. Patented Nov. 19, 1913.

Application filed December 3, 1917. Serial No. 205,196.

To all whom it may concern:

Be it known that I, HERBERT G. IRWIN, a citizen of the United States, residing at Spur, in the county of Dickens and State 5 of Texas, have invented certain new and useful Improvements in Vacuum-Operated Make-and-Break Spark-Plugs; and he does hereby declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention relates to new and useful improvements in a vacuum operated make and break spark plug; and consists of a simple and efficient device of this nature having various details of construction, combinations and arrangements of parts which will be hereinafter fully described, shown in the accompanying drawings and then specifically defined in the appended claim.

25 My invention is illustrated in the accompanying drawings which, with the letters of reference marked thereon, form a part of this specification and in which:

Figure 1 is a vertical central sectional 30 view through the invention.

Fig. 2 is a top plan view of the invention, the laterally extending portion of which is shown in section, and

Fig. 3 is a bottom plan view.

35 Reference now being had to the details of the drawings by numerals:

1 designates a plug body, and 2 is a stationary electrode mounted in a tube 5, with insulation 6 intermediate the same and the 40 electrode 2. The upper end of the electrode has a terminal connecting nut and 8 designates an oscillating electrode, with a laterally extending contact finger 3^x at its lower end and which electrode 3 is mounted in a 45 suitable guide member 7 held within the plug and in which latter a suitable lubrication, designated by letter 9, is placed in or-

der to lubricate the bearing part of said electrode 3. A coiled spring 10 is mounted over the shouldered portion of the guide 50 member 7 and bears intermediate the latter and the under surface of an arm 8, which has an angular outlined opening therein to receive the angled portion of the electrode 3. Said arm 8, as shown clearly in Fig. 2 of 55 the drawings, has beveled connection at one end with a link 14, which in turn is pivotally connected to the lug 14^x upon the piston 13 mounted within the vacuum cylinder 4, and 17 is a spring interposed between the 60 piston 13 and the wall of the vacuum chamber with which the pipe 15 communicates, and which latter is adapted to communicate with the source of vacuum.

In operation, it will be noted that by the 65 varying impulses imparted to the piston, incident to the vacuum formed in the engine, the oscillating electrode will be actuated so as to regulate the sparking of the plug to the work required of the same as the engine 70 operates.

What I claim to be new is:—

A vacuum-operated make and break spark plug comprising a shell, a tube mounted therein, an electrode passing through said 75 tube and shell and suitably insulated therein, a spring actuated oscillating electrode passing through an aperture in the bottom of the shell and having a beveled shoulder engaging the marginal edge of the aperture, 80 a guide member within the shell terminating a slight distance above the bottom of the shell and through which member said oscillating electrode passes, an arm fitted to the top of the oscillating electrode, a vacuum 85 chamber, a spring pressed piston mounted therein, and a link pivotally connecting said piston and arm.

In testimony whereof I hereunto affix my signature in presence of two witnesses.

HERBERT G. IRWIN.

Witnesses:

L. R. BARRETT,
T. L. HIGGINBOTHAM.
